CLAIM

The ornamental design for connectible smartphone, as shown and described.

DESCRIPTION

FIG. 1 is a front, right, top perspective view of connectible smartphone, showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines illustrate portions of the connectible smartphone that form no part of the claimed design.

1 Claim, 6 Drawing Sheets
